UNITED STATES PATENT OFFICE.

THOMAS L. EASLEY, OF LADDONIA, MISSOURI.

AUTOMATIC GRAIN-WEIGHER.

SPECIFICATION forming part of Letters Patent No. 295,373, dated March 12, 1884.

Application filed September 12, 1883. (Model.)

To all whom it may concern:

Be it known that I, T. L. EASLEY, a citizen of the United States of America, residing at Laddonia, in the county of Audrain and State 5 of Missouri, have invented certain new and useful Improvements in Automatic Grain-Weighers, of which the following is a specification, reference being had therein to the accompanying drawings.

10 This invention pertains to improvements in grain-sackers for thrashing-machines, having for its object to effect the sacking of the grain while being thrashed; and it consists of sack-supporting platforms combined with a valved 15 hopper whose valve is adapted to be operated by certain mechanism, and controls the direction of the grain received into the hopper, substantially as hereinafter more fully set forth and claimed.

20 In the accompanying drawings, Figure 1 is a rear view of my grain-sacking apparatus with that side of the inclosing-case removed. Fig. 2 is a vertical section thereof. Fig. 3 is a front view of the same.

25 In carrying out my invention I employ a casing, A, with an upper closed compartment, A', and two open compartments, A² A², and which is designed to be suitably secured to the thrasher at the discharging end of the latter.

30 Within the closed compartment or chamber A' is arranged and secured the hopper B, with its mouth preferably secured about flush with the top of the casing A, while its lower end is provided with two broad spouts or tubes, B' B', 35 leading to the lower open compartment, A², and projecting through the bottom of the compartment or chamber A. To the under side of said bottoms are designed to be secured suitable hooks, or other means adapted to support the mouth of the sack intended to receive the grain.

40 C C are platforms arranged in the open compartments, and secured upon side bars, C' C', which extend into the closed compartment, 45 and have coiled or other suitable springs, B² B', applied thereto, said springs bearing upon cross-pins inserted through the upper ends of the side bars and upon the bottom of the closed compartment. Through these side bars, be- 50 low cross-heads or boards C², arranged upon the said bars, are inserted additional cross-pins, a a, to hold the springs B B under ten-

sion, the springs having previously been compressed to a pressure equal to the capacity in weight of the sack placed upon each platform. 55 To each of the cross-heads C² is secured a slotted bar or projection, b, extending through an aperture in the bottom of and into the closed chamber A', the function of which will appear hereinafter.

60 D D are elbow-levers pivoted at their angles to the bottom of the closed chamber, the free end of one arm of each lever projecting into the slot of the coincident projection or bar b of the platform cross-head, while the 65 free end of the other arm enters a mortised cross bar or rod, E. The cross-rods E are each provided with a spring, c, preferably arranged so as to encircle the former, its inner or one end bearing against cross-pins d, 70 passed through the rod, while its other end bears against the front inside of the inclosed chamber A', the forward ends of the spring-rods E bearing in apertures in the same side of the said case.

75 F is a lever centrally pivoted upon the rear or projecting end of the axis of the valve G of the hopper B, and having weights F' suspended by cords (or rods) f from its ends. Said weights (in lieu of which springs may be 80 used) are notched on their inner sides, near their upper ends, as at f', to receive the pointed rear ends of the spring-rods E.

The operation is as follows: With the valve G of the hopper standing so as to open the 85 entrance or receiving end of one or the other of the tubes or spouts B' of the hopper, (only in one of either of these positions it can stand,) the grain received into the hopper will flow through the open tube or spout B' and into 90 the sack previously adjusted in position thereunder, as above explained. When the sack has about filled, the platform upon which it rests will descend by reason of the compression of the springs of the side bars of said platform. The platforms C² and C² are thus caused to descend alternately, each being rigidly secured to two of the vertical side bars, C'. Beam F has projecting through slot s in its center the valve-bar F², which forms the only 95 bearing of the beam, and hence the valve G is thrown to the right or left by descent of the weights F, and the descending grain is 100 thus directed into the spouts alternately; but

the weight of the grain is not of itself sufficient to cause the outflow of the grain to be cut off instantly, which is the essential element of my invention, as the springs first act and then react under impulse of the descending grain, and prevent the weight of grain being precisely and accurately emptied into the sacks; hence simultaneously with the descent of the grain and platform the slotted projection or bar 10 *b* of the cross-head platform side bars acts upon the coincident elbow-lever *D*, which causes its spring-rod *E* to retract from the notch of the coincident weight *F'*, and allows this weight to descend upon its platform, thus adding to the weight of the grain its auxiliary weight as a means of instantly and securely closing the valve *G*, whereby the grain is measured in just as accurate and precise a manner as obtains ordinarily after the most 15 careful manipulation. The shifting action of the valve will be repeated automatically at 20

the conclusion of each filling operation of the sacks, whereby while one sack is being emptied another is filling.

Having thus fully described my invention, 25 I claim and desire to secure by Letters Patent—

1. In a grain-weigher, the combination of the hopper *B*, having valve *G* and spouts *B'*, platforms *C*, having cross-heads *C'*, springs *B'*, and weights *F'*, substantially as shown, 30 and for the purpose described.

2. In a grain-weigher, the combination of the platforms *C'*, notched weights *F'*, secured to lever *F*, actuating-valve *G*, elbow-lever *D*, and spring-rod *E*, substantially as shown and 35 described.

In testimony whereof I affix my signature in presence of two witnesses.

THOMAS L. EASLEY.
